UNITED STATES PATENT OFFICE.

SETH B. HENSHAW, OF CHARLESTON, WEST VIRGINIA, ASSIGNOR TO CHARLESTON WINDOW GLASS CO., OF CHARLESTON, WEST VIRGINIA, A CORPORATION OF WEST VIRGINIA.

TAKE-DOWN DEVICE.

1,188,173.

Specification of Letters Patent. Patented June 20, 1916.

Original application filed September 2, 1915, Serial No. 48,634. Divided and this application filed February 10, 1916. Serial No. 77,450.

To all whom it may concern:

Be it known that I, SETH B. HENSHAW, a citizen of the United States, and a resident of Charleston, in the county of Kanawha and State of West Virginia, have invented a certain new and useful Improvement in Take-Down Devices, of which the following is a specification.

My present invention relates generally to window glass machinery of the general nature described and shown in my co-pending application Number 48634, filed September 2, 1915, of which the present application is a division.

More particularly speaking, my present invention relates to mechanism utilized in connection with window glass machinery, to take down the drawn glass cylinders preparatory to capping the same into lengths, which lengths are thereafter flattened out into the finished sections of window glass.

The object of my present invention is to provide a take-down device, simple and effective in itself, and capable of simple and effective control with the use of but a single winding drum and main cable to be wound thereon.

In the accompanying drawings illustrating my invention: Figure 1 is a vertical transverse section through a glass furnace in connection with which my improvements are utilized. Fig. 2 is a similar view of a part of one side only, on an enlarged scale. Fig. 3 is a detail plan view of the main drum and its driving means. Fig. 4 is a detail perspective view of the controlling connections for the clutch of the main drum shown in Fig. 3. Fig. 5 is a detail end view of the take-down drum, and Fig. 6 is a detail of the clamp connection of the take-down cables.

In Figs. 1 and 2 in particular, are shown drawing chambers A² and A³ at opposite sides of, and in communication with, the melting chamber A' of the furnace A, the latter having suitable bindings as at B extending upwardly and joining the superstructure B' in which, among other things, are pivotally mounted the upper ends of the guides C, one for each drawing chamber. Each of these guides supports a vertically movable cage D as usual, on which the bait E is to be removably seated for the drawing operation.

Each bait cage D just above mentioned is, in operation of the machinery, drawn vertically by a cable D', from the main winding drum D², driven from a motor D³, and under control of a clutch D⁴ which is in turn under control of a hand lever D⁵ in the operator's box F, through certain leverage connections D⁶ as seen in Figs. 3 and 4. When the clutch D⁴ is thrown in, the drum D² is gradually rotated to wind the drawing cable D' thereon, gradually drawing the cylinder which, after being cut off, is free to descend, carriage D then moving downwardly in guide C, when the clutch D⁴ is withdrawn.

For taking down the cylinder when drawn, and after being cut off at its bait from the molten mass of glass, use is made, in accordance with my present improvements, of a main take-down cable N, passing over rollers N', one end of this cable being secured to the superstructure B² as plainly seen in Figs. 1 and 2, and the other end leading to and around a take-down drum L. This cable N supports a trolley N² carrying a hoop N³ capable of encircling the lower cut-off end of a drawn cylinder when the latter is moved outwardly with the outward movement of the lower portion of the respective guide C, as shown at the left of Fig. 1.

To the above mentioned main take-down cable N is attached one end of a counter-weighted controlling cable O, the connection being made by a clamp P above the level of the floor M and which clamp reaches the floor and limits further movement when the cable is wound on take-down drum L to a point sufficiently to properly elevate the lower end of the drawn cylinder. During the drawing of a cylinder, however, cable N with its trolley N² is on the floor with the weight O' at the outer end of controlling cable O in lowermost position. Attached also at one end to the above mentioned main take-down cable N, by the clamp P, is a bait-catching cable Q, the opposite end of which carries a hook Q³ engageable with a loop E' of the bait E as shown in Fig. 2. Intermediate its ends, this cable Q passes over spaced rollers Q' and is provided between these rollers with a counter-weight Q² by which the slack may be taken up during the drawing of the cylinder, as the bait E and its

cage D before mentioned, move upwardly in the guides C. But when a cylinder is fully drawn, the weight Q² of the cable Q is in its lowermost position, as is also the weight O' of cable O, clamp P being in its raised position. When the lower end of the cylinder is cut off and the hoop N² disposed therearound, the control operator in the box F pulls down upon the lever I which, through a flexible connection I', actuates a belt tightener I² operating against a normally loose belt L' forming one of the intermediate power transmitting elements between the take-down drum L and the motor G of the take-down apparatus. Upon such act, therefore, rotation is imparted to the take-down drum to wind the take-down cable thereon, in the course of which the clamp P is drawn down to the floor M, raising the cable N and its hoop N² and swinging the lower end of the drawn cylinder outwardly and upwardly.

The take-down drum L is normally engaged and held in immovable relation upon its shaft L² as seen in Fig. 5, by means of a flexible band brake L³ connected at its ends to a lever L⁴ upon opposite sides of the pivot L⁵ of the latter, this lever being in turn acted upon by a spring L⁶ normally maintaining the brake band in close contact with the drum. To the lever L⁴ is attached one end of a flexible connection J' leading to a foot lever J in the operator's box F which must be depressed before the belt tightener I² is actuated as before described to transmit rotation to the drum. During the movements of the take-down drum to wind its cable thereon, the slack only of cable Q is taken up, its weight Q² being drawn upwardly to the rollers Q'. The lever I is then released and foot lever J upon being depressed, releases the brake L³ from the take-down drum and thus permits the bait and its cage to lower, as soon as the clutch D⁴ of the main winding drum is released by actuating the lever D⁵. During the lowering movement of the head end of the cylinder with the bait thereon, clamp P is drawn upwardly and trolley N² is free to move outwardly on the cable N. Before the cage D reaches its lowermost position, the foot lever J is released and brake L³, automatically engaging the take-down drum, checks further movement of the cable. Bait E being removably seated on the cage D as usual, is, due to the foregoing, withdrawn entirely from the cage, and the finished cylinder swings freely out over the usual capping horse R as clearly seen at the right in Fig. 1. It may then be gradually lowered onto the capping horse by again depressing foot lever J to allow of its further downward movement, after which brake L³ is again released, and weight O' assists in unwinding the remaining part of the take-down

cable from drum L, so that when detached from the cylinder, the trolley N² may rest upon the floor between operations. I am thus enabled to effectively take down and control the drawn glass cylinder without a multiplicity of cables and winding drums, and by, in fact, using but a single drum and a single cable on the drum.

I claim:—

1. In window glass machinery, a cylinder drawing mechanism including a bait and its cage, and a take-down mechanism, the latter including a take-down cable anchored at one end and having a trolley provided with cylinder engaging means, a drum on which the opposite end of said cable is wound, driving means for said drum, means for engaging said drum with, and disengaging the same from, said driving means, and a counter-weighted cable and a bait engaging cable attached to said take-down cable intermediate its ends, said bait engaging cable being attachable at its opposite end to the bait.

2. A take-down apparatus including a freely revoluble take-down drum, driving means therefor, manually controlled connections between the said drum and the said driving means, a manually controlled brake engageable with the said drum, a main take-down cable anchored at one end and having its opposite end attached to the drum, a trolley movable on the said cable and provided with cylinder engaging means, a bait engaging cable having a hook at one end and attached at its opposite end to the said take-down drum at a point intermediate the ends of the latter, a pair of pulleys over which the said bait engaging cable is intermediately extended, a weight secured to the said bait engaging cable at a point between said pulleys, a controlling cable attached at one end to the take-down cable at a point intermediate the ends of the latter, and provided at its opposite end with a controlling weight, and guides over which the said controlling cable is intermediately extended.

3. A take-down apparatus including a manually controlled take-down drum, a take-down cable anchored at one end and having its opposite end attached to the drum, a cylinder engaging trolley carried by the take-down drum, a bait engaging cable having a bait engaging hook at one end and attached at its opposite end to the said take-down cable at a point intermediate the ends of the latter, a pair of pulleys over which the bait engaging cable is intermediately extended, and a weight attached to the said bait engaging cable at a point between the said pulleys.

4. A take-down apparatus including a manually controlled take-down drum, a take-down cable anchored at one end and secured at its opposite end to the said drum, a cylinder supporting trolley carried by said take-

down drum, and a bait engaging cable having bait engaging means at one end and connected at its opposite end to the said take-down drum intermediate the ends of the latter, and provided with slack absorbing means intermediate its ends.

5. A take-down apparatus including a manually controlled take-down drum, a take-down cable anchored at one end and having its other end attached to the said drum, a bait engaging cable having bait engaging means at one end and attached at its oppo-

site end to the take-down cable, and provided intermediate its ends with slack absorbing means, and a controlling cable attached at one end to the take-down cable at a point intermediate the ends of the latter and having a weight at its opposite end for the purpose described. 15
